(57) **CLAIM**

The ornamental design for a display screen with a graphical user interface, as shown and described.

DESCRIPTION

FIG. 1 illustrates a first image of a graphical user interface on a display screen;

FIG. 2 illustrates a second image of a graphical user interface on a display screen;

FIG. 3 illustrates a third image in a first sequence for a display screen with a graphical user interface, where the first sequence transitions from the first image of the display screen shown in FIG. 1 to the third image of the display screen shown in FIG. 3; and,

FIG. 4 illustrates a fourth image in a second sequence for a display screen with a graphical user interface, where the second sequence transitions from the fourth image of the display screen shown in FIG. 4 to the first image of the display screen shown in FIG. 1.

The broken-line drawings of the display screen and other portions of the graphical user interface are for illustrative purposes only and form no part of the claimed design.

The subject matter shown herein for the first sequence includes a process or period in which the graphical user interface shown on the display screen transitions from the first image shown in FIG. 1 to the third image shown in FIG. 3. This process or period in which one graphical user interface on a display screen transitions to another graphical user interface on a display screen forms no part of the claimed design.

The subject matter shown herein for the first sequence includes a process or period in which the graphical user interface on a display screen shown on the display screen transitions from the fourth image shown in FIG. 4 to the first image shown in FIG. 1. This process or period in which one graphical user interface on a display screen transitions to another graphical user interface on a display screen forms no part of the claimed design.
